UNITED STATES PATENT OFFICE

LOUIS J. SAUER, OF OAK PARK, ILLINOIS, ASSIGNOR TO CHARLES H. JOY, SR., OF CHICAGO, ILLINOIS

MARGIN BAR

Application filed July 15, 1929. Serial No. 378,262.

My invention relates to adjustable margin bars and feeding devices for duplicating machines with special reference to that class of machines provided with a flat gelatinized printing surface over which a platen carriage having a suitable platen roller is arranged to travel.

In this type of machine, the paper, or a suitable card is inserted in the carriage and the platen roller impresses the original or the copy sheet on the gelatinized printing surface which receives the impression from the original sheet and transfers it to the copy sheet.

15 My invention is particularly adapted for use in connection with machines similar to that shown and described in my copending application Serial No. 349,876.

In positioning the original or copy sheets 20 on the gelatinized surface it is necessary to provide a suitable margin stop bar in order that the desired uniform margin will be obtained on the copies and that the paper may be accurately located with relation to the carriage and feed rolls.

In my invention I have provided a convenient means for accomplishing the desired results and it has for one of its objects the provision of a combined adjustable margin 25 bar and feeding device which will provide an effective paper locating means and which will not interfere in any way with the operation of the carriage or the movement of the platen roller.

30 Another object is to provide an automatic adjustable margin bar in which the width of the margin may be predetermined and accurately adjusted.

Another object is to provide a margin bar 35 automatically controlled by the operator through the normal movement of the carriage handle.

A further object is the provision of a manually adjustable automatically controlled margin bar which is supported on and carried by the carriage.

Further objects will appear from the detailed description to follow and from the appended claims.

In the drawings,—

Figure 1 is a side elevation of the carriage and of cooperating parts of a duplicating machine embodying my invention;

Fig. 2 is a sectional plan view taken on a line corresponding to line 2—2 of Fig. 3;

Fig. 3 is a sectional elevation, the section being on a line corresponding to line 3—3 of Fig. 2;

Fig. 4 is a detailed section taken on line 4—4 of Fig. 3;

Fig. 5 is a detailed perspective view of the margin bar releasing member;

Fig. 6 is a perspective view of a portion of the margin bar and its supporting shaft to which it is rigidly attached; and

Fig. 7 is a view of one end of the platen roll and its bearing, partly in section, taken along line 7—7 of Fig. 2.

Referring now to the drawings in detail, my invention as illustrated comprises a printing bed 1 having a gelatinized printing surface 2 thereon.

I have illustrated my invention as embodied in a machine of the usual construction 75 in which the guide bar 3 is supported adjacent the printing bed and on which is slidably mounted the carriage 4 which is also arranged to be raised from the bed surface by partial rotation on the shaft 3.

The carriage is preferably in the form of a substantially rectangular framework in which is mounted the removable platen roller 5 in suitable bearings 6 and 7. The bearing 6 comprises the stub shaft 8 on which is mounted the driving spool 9 for driving the platen roller. This roller is similar to that in my co-pending application above mentioned, the platen roller being rotated in the usual manner by means of a single turn of the cable 10 which engages the flanged spool 9.

The squared portion 11 of the platen roller shaft, engages in a suitable opening in the stub shaft 8 for supporting and driving the platen roller. The opposite end of the roller 12 is engaged by the tapered pin 12 which is held in engagement by means of the spring 13. The platen roller is easily removable by pulling the knurled handle 14 and compressing the spring.

The pressure roller 15 is mounted adjacent the platen roller and is driven at the same surface speed by means of the gears 16 and 17. The gear 16 in the present construction, forms a part of the pulley 18 which is used for driving the feeding device to be described later.

The paper table 19 is pivotally mounted at 19a on the upwardly extending portion 20 of the carriage frame and is arranged for angular adjustment with relation to the rollers 16 and 17 by means of the adjusting screws 21. The correct adjustment of the paper table by these screws insures the entrance of the paper between the platen roller 5 and the pressure roller 15.

The margin bar 22 is rigidly secured to the shaft 23 and slidably supported in the slots 24 in the upturned ears 25 on the paper table. The shaft 23 extends through these slots and is movable therein.

The margin bar is adjustable to any desired position within the limit of the slots 24 by means of the thumb nut 26 on the rod 27 which is rotatably mounted on the carriage 4 as illustrated in Fig. 1.

The collar 28 is threaded on the rod 27 and arranged for longitudinal movement thereon. When the thumb nut 26 is turned the collar 28 moves the lever 29 rearwardly and rocks the shaft 30 which is mounted in suitable bearings on the carriage. The shaft 30 is provided with arms 31 which are connected to the ends of the margin bar shaft 23 by means of the links 32, the links being loosely connected to the margin bar shaft. By means of this construction, when the thumb nut 26 is rotated the margin bar will be moved up or down the paper table to any desired position within the limit of the slots 24.

In order that the depending stop portion 33 of the margin bar 22 may be held in contact with the paper table, an arm 34 is rigidly connected to the margin bar shaft and is provided with the pin 35 extending through the slot 36 in the upturned portion 37 of the margin bar releasing member 38. The member 38 is hinged beneath the paper table by means of the pivots 39 engaging in the downturned ears 40 as illustrated in Figs. 2, 3 and 4. The member 38 is normally held in the position illustrated in Fig. 4 by means of the spring 41 and in this position the margin bar is held in engagement with the paper table and in a position to support any paper laid thereon.

The releasing member 38 is provided with the outwardly extending ear 42 and it is obvious that when the ear 42 is pushed downwardly the margin bar will be raised from the paper table through the cooperation of the pin 35 engaging in the slot 36.

In order that the carriage may be moved back and forth over the printing surface it is provided with the handle 43. This handle is secured to the shaft 44 which is pivoted in the frame of the carriage 4.

A pin 45 on the carriage is arranged to engage in the notch 46 in the handle to allow a limited movement of the handle with relation to the carriage.

A link 47 is connected to the handle and extends to a point adjacent the ear 42 of the margin bar releasing member. When the handle is pushed rearwardly to move the carriage over the printing surface the limited movement of the handle with relation to the carriage allows the end of the link 47 to move downwardly and engage the ear 42 moving the releasing member 38 downwardly and raising the margin bar and allowing any paper which may have been placed on the paper table to be released.

In order that the paper when released by the margin bar may be moved into engagement with the platen roller and pressure roller, I have provided an automatic paper feeding device comprising a roller 48 supported on the arms 49 which are pivotally mounted in alignment with the shaft of the platen roller as illustrated. The roller 48 is rotated from the platen roller shaft by means of the belt 50 and the pulleys 18 and 51.

The arms 49 are provided with pins 52 engaging in the slots 53 in the links 47. The relative position of the pins in the slots causes the roller 48 to be held out of engagement with the paper table when the handle is in the forward position illustrated in the drawings.

When the handle is moved rearwardly the limited movement of the handle which raises the margin bar also releases the roller 48 for engagement with the paper on the paper table. The timing of these movements is such that the roller engages the paper at approximately the same time that it is released by the margin bar, and as the carriage is then moved rearwardly the roller 48 will be rotated by means of the belt and pulleys previously described and the paper will be forced downwardly between the platen and pressure rollers and be impressed on the printing surface in any predetermined marginal relation to which the margin bar has previously been adjusted.

The roller 48 is held normally under downward tension by means of a spring 54. The bar 55 adjacent the platen and pressure rollers provides a suitable guide for the paper as it passes between the platen and pressure rollers and also guides the paper in its return movement between the rollers as the carriage moves forward and assists in removing the paper from the gelatinized surface.

In the construction shown there is at all times a slight pressure of the platen roller against the gelatinized surface and I have found it desirable to provide a means adjacent the platen roller for moistening the printing surface. This is accomplished by means of the hollow cylindrical tank 60 which is pivoted at 61 on the carriage and extends across the printing surface. The tank is adapted to

contain water as illustrated and is provided with a suitable wick 62 for engagement with the gelatine surface. The wick is removed from contact when desired by rotating the tank by means of the handle 63.

It is obvious that various changes in the details of the construction shown may be made without departing from the spirit of the invention.

10 Having thus described my invention, what I claim and desire to secure by Letters Patent is:

1. In a duplicating machine, a carriage arranged to travel over the printing bed, a paper table on said carriage, a paper stop cooperating with said table to support paper thereon, means for adjusting the position of said stop relative to said table, and automatic means controlled through the normal operation 20 of the carriage to release the paper and deliver it on the printing bed in a position determined by the adjusted position of the paper stop.

2. A duplicating machine having platen and pressure rollers and a paper table in co-operative relation, a carriage for said rollers and table, operating means for said carriage, an adjustable paper stop on said table adjacent said rollers, means for adjusting the position 25 of said paper stop to provide a desired margin, and automatic means for moving said paper stop to inoperative position upon movement of the carriage operating means.

3. A duplicating machine having platen and pressure rollers and a paper table for receiving paper, a carriage for said rollers and table, operating means for said carriage, an adjustable paper stop adjacent said rollers and cooperating with said paper table, means 30 for adjusting the position of said paper stop to provide a desired margin, means to move said paper stop to release said paper, and paper feeding means to feed said paper to said rollers to provide a margin corresponding to 40 the position of the paper stop.

4. In a feeding device for duplicating machines having a carriage arranged to travel over a printing bed, means for controlling the normal movement of said carriage, a paper table for receiving paper, an adjustable paper stop supported on said table, and means cooperating with said paper stop and said carriage controlling means to release said paper on the normal operation of said carriage controlling means.

5. In a feeding device for duplicating machines having a carriage arranged to travel over a printing bed, means for controlling the normal movement of said carriage, a paper table for receiving paper, an adjustable paper stop supported on said table, means for adjusting the relative position of said stop, means cooperating with said paper stop and said carriage controlling means to release said paper, and means to deliver the paper on the

printing bed in a position determined by the adjusted position of the paper stop, both of said last named means being automatically controlled through the normal operation of said carriage.

6. A duplicating machine comprising a printing bed, a carriage arranged to travel over said bed, platen and pressure rollers on said carriage, means for driving said rollers at substantially the same surface speed, means for feeding paper to said rollers comprising a paper table, a paper stop adjustably mounted on said table, means for accurately adjusting the position of said stop, yielding means for holding said stop normally in paper engaging position, a feed roller, spring means tending to hold said feed roller in engagement with said paper, a limited movement handle for operating said carriage, and means controlled by the limited movement of said handle for holding said feed roller out of engagement when the handle is in one position and for releasing said roller and operating said yielding means to move said paper stop when the handle is moved to the opposite limited position.

7. In a duplicating machine having a gelatinized printing surface, a carriage arranged to travel over said surface, platen and pressure rollers arranged to deliver paper to said surface, and means on said carriage to moisten said gelatinized surface during the travel of said carriage.

8. In a duplicating machine having a carriage arranged to travel over a printing surface, a platen roller arranged for contact with the printing surface, means for supplying moisture to said surface comprising a rotatable tank mounted on said carriage, and a wick communicating with the interior of said tank, said tank being rotatable to move said wick into and out of engagement with said printing surface.

9. In a duplicating machine having a carriage arranged to travel over a printing bed, a handle for operating said carriage, said handle having a limited lost motion relative to the carriage, a paper table on said carriage, a paper releasing adjustable margin bar, means for adjusting said margin bar with respect to the table to vary the margin, and means operable through the lost motion movement of said handle to operate said margin bar.

10. In a duplicating machine having a carriage arranged to travel over a printing bed, a handle for operating the carriage and having a limited lost motion relative to said carriage, a paper table on said carriage, a paper releasing adjustable margin bar on said carriage, means for adjusting said margin bar with respect to the table to vary the margin, a paper feeding device cooperating with said margin bar, and means including the handle for controlling the operation of said margin bar.

bar and said paper feeding device through the lost motion movement of said handle.

11. In a duplicating machine having a carriage arranged to travel over a printing bed, a handle for operating the carriage and having a limited lost motion relative to said carriage, a platen roller on said carriage and arranged to be driven by the movement of said carriage, a paper table, a margin bar for controlling the relative position of the paper, means for adjusting said margin bar with respect to the table to vary the margin, a paper feeding device operable through the movement of the carriage and means including the handle for controlling the operation of the margin bar and the paper feeding device through the lost motion movement of said handle.

12. In a duplicating machine having a carriage arranged to travel over a printing bed, a handle for operating the carriage and having a limited lost motion relative to said carriage, platen and pressure rollers carried by said carriage, means for driving said rollers through the movement of the carriage, means operable by said platen operating means for feeding paper between said rollers, a margin bar adjustable to control the relative position of the paper, and means including the handle for controlling the relative operation of said margin bar and said feeding device through the lost motion movement of the handle.

13. A duplicating machine construction comprising a carriage mounted to travel back and forth over a transfer surface, an inclined table on said carriage for supporting a sheet to be applied to the transfer surface, a platen roller mounted on said carriage for pressing the sheet on the transfer surface, and feeding means for pressing the sheet against the table and feeding it downwardly therealong to be acted on by the platen roller.

14. A duplicating machine construction comprising a carriage mounted to travel back and forth over a transfer surface, an inclined table on said carriage for supporting a sheet to be applied to the transfer surface, a platen roller mounted on said carriage for pressing the sheet on the transfer surface, and feeding means for pressing the sheet against the table and feeding it downwardly therealong to be acted on by the platen roller, said feeding means comprising a roller and means for rotating said roller.

15. A duplicating machine construction comprising a carriage mounted to travel back and forth over a transfer surface, an inclined table on said carriage for supporting a sheet to be applied to the transfer surface, a platen roller mounted on said carriage for pressing the sheet on the transfer surface, and feeding means for pressing the sheet against the table and feeding it downwardly therealong to be acted on by the platen roller, said feeding means comprising a roller and a bearing

frame on which said roller is mounted shiftable to move the roller toward and from the table to bring it into and out of feeding position with respect to the sheet.

16. A duplicating machine construction comprising a carriage mounted to travel back and forth over a transfer surface, an inclined table on said carriage for supporting a sheet to be applied to the transfer surface, a platen roller mounted on said carriage for pressing the sheet on the transfer surface, and feeding means for pressing the sheet against the table and feeding it downwardly therealong to be acted on by the platen roller, said feeding means comprising a roller and a bearing frame on which said roller is mounted shiftable to move the roller toward and from the table to bring it into and out of feeding position with respect to the sheet, and a handle for effecting the travel of the carriage having a lost motion mounting on said carriage and connected with the feed roller frame whereby the lost motion of the handle is used in shifting the feed roller frame.

17. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, and means for feeding the sheet to the platen roller when the retaining means are moved to releasing position.

18. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, and means for feeding the sheet to the platen roller when the retaining means are moved to releasing position, comprising a feed roller engaging the sheet.

19. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, and means for feeding the sheet to the platen roller when the retaining means are moved to releasing position, comprising a feed roller engaging the sheet, and means for driving the roller.

20. In a duplicating machine, a carriage mounted to travel over a printing surface, a

platens roller mounted on said carriage for pressing the sheet on the printing surface, a support on which the sheets rest prior to passing underneath the roller, retaining means for holding the sheet on the support movable to releasing position to permit the sheet to pass underneath the roller, and means for feeding the sheet to the platen roller when the retaining means are moved to releasing position, comprising a feed roller engaging the sheet, said feed roller being movable into and out of engagement with respect to the sheet.

21. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, means for feeding the sheet to the platen roller when the retaining means are moved to releasing position, comprising a feed roller engaging the sheet, said feed roller being movable into and out of engagement with respect to the sheet, and a handle for moving the carriage and controlling the movement of the feed roller with respect to the sheet.

22. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, means for feeding the sheet to the platen roller when the retaining means are moved to releasing position, comprising a feed roller engaging the sheet, said feed roller being movable into and out of engagement with respect to the sheet, a handle for moving the carriage and controlling the movement of the feed roller and retaining means with respect to the sheet.

23. In a duplicating machine, a carriage mounted to travel over a printing surface, a platen roller mounted on said carriage for pressing the sheet on the printing surface, a support on which the sheets rest prior to passing underneath the roller, and retaining means for holding the sheet on the support movable to releasing position to permit the sheet to pass underneath the roller, said retaining means comprising a retaining member movable upwardly to release the sheet and downwardly to retain it.

24. In a duplicating machine, a carriage mounted to travel over a printing surface, a platen roller mounted on said carriage for pressing the sheet on the printing surface, a support on which the sheets rest prior to passing underneath the roller, and retaining

means for holding the sheet on the support movable to releasing position to permit the sheet to pass underneath the roller, said retaining means comprising a member mounted to swing about an axis above the sheet support. 70

In witness whereof, I have hereunto subscribed my name.

LOUIS J. SAUER.
